DESIGN FOR A VENTILATING FAN HOUSING

Bernard M. Sallot, Cleveland Heights, and Maximilian Paul Hofmann, Bay Village, Ohio, assignors to Wilster Incorporated, Cleveland, Ohio, a corporation of Ohio

Application July 25, 1947, Serial No. 140,512

Term of patent 3½ years

(Cl. D62—4)

To all whom it may concern:

Be it known that we, Bernard M. Sallot and Maximilian Paul Hofmann, citizens of the United States and residents of Cleveland Heights and Bay Village, Cuyahoga County, Ohio, respectively, have invented a new, original, and ornamental Design for a Ventilating Fan Housing, of which the following is a specification, reference being had to the accompanying drawing, forming a part thereof.

In the drawing, Fig. 1 is a front elevational view

of a ventilating fan housing showing our new design. Fig. 2 is a top plan view of the same; while Fig. 3 is an end elevational view of the same, both ends being alike.

We claim:

The ornamental design for a ventilating fan housing, as shown and described.

BERNARD M. SALLOT.

MAXIMILLIAN PAUL HOFMANN.
